UNITED STATES PATENT OFFICE.

JOHN D. McELYA, OF METROPOLIS CITY, ILLINOIS.

STUMP-EXTRACTOR.

SPECIFICATION forming part of Letters Patent No. 438,634, dated October 21, 1890.

Application filed July 5, 1890. Serial No. 357,844. (No model.)

To all whom it may concern:

Be it known that I, JOHN D. McELYA, a citizen of the United States, residing at Metropolis City, in the county of Massac and 5 State of Illinois, have invented a new and useful Stump-Extractor, of which the following is a specification.

The invention relates to improvements in stump-extractors.

10 The object of the present invention is to simplify and improve the construction of stump-extractors and increase their strength and durability, and enable the sweep-lever to conform to the motion of the draft-animals 15 without interfering with the rotation of the screw.

The invention consists in the construction and novel combination and arrangement of parts hereinafter fully described, illustrated 20 in the accompanying drawings, and pointed out in the claim hereto appended.

In the drawings, Figure 1 is a perspective view of a stump-extractor constructed in accordance with this invention. Fig. 2 is a vertical sectional view. Figs. 3 and 4 are detail perspective views of the cap-plate and the nut.

Referring to the accompanying drawings, 1 designates a derrick or frame approximately pyramidal in shape and having its 25 upper end truncated and composed of four inclined standards 2 and horizontal cross-pieces 3, arranged at different elevations and connecting the standards. The upper ends 30 of the standards are connected by a square plate 4, which is bolted to the standard and is provided with a central opening 5, and a socket 6, surrounding the opening and having its upper face concave. The lower ends 35 of the standards are secured to runners 7, provided with a chain 8, having centrally attached to it whiffletrees 9, by which the stump-extractor is moved from place to place. The 40 socket of the square plate 4 is engaged by the lower convex face 10 of a nut 11, that has a central threaded opening to receive a screw 12, depending from the square plate 4, and provided at its lower end with a ring 13 and adapted to be connected with a stump in the

usual manner by chains 14 and hooks 15. 50 The convex face of the nut fits in the concave socket and is adapted to move freely therein and permit a sweep-lever 16, secured to the nut to freely conform with the motion of the draft-animal without interfering with 55 the screw, which is much smaller than the central opening 5 in the square plate. The convex or semi-spherical nut has formed integral with its upper flat face a plate 17, projecting beyond the nut and provided with 60 perforations, through which pass bolts that secure the sweep-lever to the plate and nut, and the said plate is provided at its upper edges with longitudinal flanges 18, that project above the face of the plate and engage 65 the sides of the sweep-lever and assist in securing the same to the plate. One end of the sweep-lever is bent downward and is provided with a doubletree and singletrees, by means of which the draft-animals are secured 70 to the sweep and the screw elevated.

From the foregoing description and the accompanying drawings the construction, operation, and advantages of the invention will readily be understood; and it will be 75 seen that a double set of hooks is employed for each one of the chains 14 to facilitate attachment to a stump. The frame may, if desired, be mounted upon wheels to enable the stump-extractor to be readily moved from 80 place to place.

What I claim is—

In a stump-extractor, the combination of the frame, the rectangular cap-plate connecting the upper ends of the standards of the 85 frame and provided with a central opening and having an integral socket portion surrounding the central opening and presenting a concave upper face, the nut having a central threaded opening and consisting of a 90 plate provided on its lower face with an integral convex or rounded enlargement bearing in the socket portion and moving freely therein, said plate having an upper flat face, and having its ends perforated and extending beyond the enlargement and being provided with parallel longitudinal flanges 95 arranged at its side edges and standing from

its face and forming a box or casing, the sweep-lever arranged in the box or casing and secured to the plate at a point intermediate of its ends, and the screw engaging the 5 threaded opening of the nut and provided with a ring and the usual chains and hooks, substantially as described.

In testimony that I claim the foregoing as my own I have hereto affixed my signature in presence of two witnesses.

JOHN D. McELYA.
